J. LATIMORE,
GARMENT PATTERN,
APPLICATION FILED MAR. 15, 1920.

Patented May 30, 1922.

INVENTOR.
JOHN LATIMORE.

BY
Thomas L. Wilder
ATTORNEY.

UNITED STATES PATENT OFFICE.

JOHN LATIMORE, OF UTICA, NEW YORK.

GARMENT PATTERN.

1,417,612.

Specification of Letters Patent. Patented May 30, 1922.

Application filed March 15, 1920. Serial No. 365,759.

To all whom it may concern:

Be it known that I, JOHN LATIMORE, a citizen of the United States, residing at Utica, in the county of Oneida and State of New York, have invented certain new and useful Improvements in Garment Patterns, of which the following is a specification, reference being had therein to the accompanying drawing.

10 My invention relates to a garment pattern and I declare the following to be a full, clear, concise and exact description thereof sufficient to enable anyone skilled in the art to which it appertains to make and use the 15 same, reference being had to the accompanying drawings in which like reference characters refer to like parts throughout the specification.

The object of the invention is to provide a 20 garment pattern for use more particularly in making men's, boys' and women's suits. The pattern is designed to economize in saving of time in cutting out said garments. Heretofore, in the use of such patterns it has been necessary to lay the pattern upon 25 the cloth and after marking with a piece of wax or chalk the general outline of the pattern to mark also the location of certain perforations which are used as guides to the 30 cutter in fitting the several parts together in an accurate manner for the formation of the coat or trousers or other design intended. To this end certain open perforations were 35 made along the edges of the respective patterns and the wax marks made accordingly. Subsequently, when the tailor removed the 40 pattern and cut the cloth to conform thereto, the chalk marks indicating the perforations and being made adjacent the cut edge 45 would become obliterated or cut away in said operation, thereby necessitating the laying of the pattern a second time upon the cloth thus cut, and remarking the perforations.

45 This operation of remarking the perforations is avoided in applicant's pattern for the reason that applicant has designed his patterns with certain perforations that are disposed one fourth of an inch from the 50 edge thereof and within the general outline of the pattern, whereby they cannot be cut away.

The object will be apparent by referring to the drawings in which:

55 Fig. 1 is a plan view of a pattern of the back of the coat;

Fig. 2 is a plan view of a pattern of the front of the coat;

Fig. 3 is a plan view of a pattern of the front of the sleeve;

Fig. 4 is a plan view of a pattern of the back of the sleeve.

Fig. 5 is a plan view of a pattern of the front of the trousers;

Fig. 6 is a plan view of a pattern of the back of the trousers.

Referring more particularly to the drawings, the patterns are made preferably of card board or of dark brown heavy paper. A complete set of patterns for making a 70 man's suit is here illustrated. The pattern for the back of a coat is represented by 75 —1—. It has two narrow slots or perforations 2—2 made within a fourth inch of the side edges which perforations are adapted to indicate the line of the neck outlet. The perforations 3—3 indicate the line along which the bottom edge of the coat should be turned up. A perforation 4 denotes the 80 location of the shoulder and is adapted to be placed upon the perforation 4 of the pattern 5 of the front of the coat shown in Fig. 2, when fitting the pieces of cloth together relative to seaming.

The front pattern 5 has perforations at 85 6—6 to indicate the line along which the bottom edge is turned up and perforations at 7—7 to indicate the line of the outlet. It also has a perforation 8 for the location of the neck outlet and at 9 for the collar outlet 90 and perforations 10—10 to indicate the line of the break or turn over part that forms the lapel of the coat. A perforation 14 indicates the location of the sleeve aperture.

The sleeve patterns are represented at 11 95 and 12 and are provided with perforations 13—13 to indicate the line along which they are turned up. Sleeve pattern 11 has a perforation 14 adapted to be applied to the perforation 14 in the front coat pattern 5 when 100 sewing the parts together.

The front trousers pattern is represented at 15. Inasmuch as there are two such portions or pieces, one of the same will be cut, along the dotted line 16 and the other along 105 the full lines as illustrated in Fig. 5, whereby to leave a little more fullness in the one side of the trousers than the other for the comfort of the wearer.

The pattern for the rear portions of the 110 trousers is represented at 17, which is cut also double and is equipped with a V-shaped

perforation 30 to allow for a take up in the waist portion over the seat. A piece 18 is sewed also along the seam 19 in order to provide for an outlet in the event of subsequent alteration to fit a particular wearer.

The front pattern 15 and back pattern 17 are adapted to be sewed together. In order to properly match said patterns 15 and 17, they are equipped with perforations 20-20 10 to indicate the waist band, perforations 21-21 for the hip, perforations 22-22 the knee and perforations 23-23 the turned up portion. The pattern 15 has also a perforation 25 to indicate the location of the fly and 15 the perforations 26-26 to indicate the side pockets. The edges of the several perforations in the patterns are reinforced with metal, whereby to prevent them from becoming easily torn.

20 In applying these patterns, the cutter or user of the same, first lays the several patterns upon the cloth and after marking with a wax or chalk along the edges and through the perforations thereof, he removes the patterns and proceeds to cut the cloth along the pattern outlines. Thereafter the perforations are made in said cloth by a pair of shears, which will cut a small perforation in the cloth a fourth of an inch from the edge of the 25 same. The location of said perforations are clearly indicated by the wax marks made through the perforations in the patterns and, inasmuch, as said perforations in the patterns are within the outline thereof, said wax 30 marks will not be cut away or obliterated, in said act of cutting thereby avoiding the necessity of reapplying the patterns and marking a second time the location of the perforations. The corresponding pieces of 35 cloth are then fitted together in such manner as to have the corresponding perforations come together and be included in the seam of the finished garment. That is the perforation 4 of the back piece 5 of the coat will be 40 placed upon the perforation 4 of the front piece 5 of said coat, whereby to properly fit said pieces together. Likewise, the perforation 14 of the front piece 11 of the sleeve will be placed upon the perforation 14 of the front

piece 5 of the coat, whereby to properly fit 50 said sleeve to said front piece 5.

In fitting together the respective parts of the trousers, the waist band perforations 20, the hip perforations 21 the knee perforations 22, and turn up perforations 23 will be placed 55 together, whereby to properly fit said parts.

Having thus described my invention what I claim as new and desire to secure by Letters Patent is:

1. In a garment pattern, parts representing the different pieces of a garment, and perforations for indicating the places where said parts are fitted together. 60

2. In a garment pattern, parts representing the different pieces of a garment, and 65 perforations disposed adjacent the edges of said parts, whereby to indicate where said parts fit together.

3. In a garment pattern, parts representing a coat, other parts for representing trousers, and perforations located adjacent the edges of said patterns, whereby to indicate 70 the proper places for fitting said pieces together.

4. In a garment pattern, having the outline of a single part thereof, perforations 75 cut therein adjacent the edge of said pattern, whereby to indicate the proper places for fitting said part to another corresponding part.

5. In a garment pattern, parts thereof representing the different pieces of a garment, perforations made adjacent the edges 80 of said parts and at given locations therealong, whereby to indicate the proper places 85 for fitting said pieces of garment together.

6. In a garment pattern, parts thereof representing the different pieces of a garment, perforations made in said parts within a given distance from the edge thereof, said 90 perforations or slots being intended for the exposure of the cloth therebelow which is located by a chalk mark, and said chalk marks being adapted to indicate the proper places for fitting the pieces of a garment together. 95

In testimony whereof I have affixed my signature.

JOHN LATIMORE.
